MANUFACTURE OF OPEN-END SHOES

Jacob S. Kamborian, West Newton, and Wilfred T. Tracy, Lynn, Mass.; said Tracy assignor to said Kamborian

Application September 22, 1943, Serial No. 503,337

5 Claims. (Cl. 36—19.5)

1

This invention pertains to the manufacture of footwear, particularly to the manufacture of shoes of the open-toe and/or open-heel variety, and especially to those made by the force-lasting method, and relates more particularly to a novel construction for such shoes, and to a method of making such shoes.

In making shoes of the open-toe or open-heel variety it is necessary to provide a finish for the edge of the middle sole where such edge is exposed at the toe or heel opening, or both. Customarily this finish is provided by applying a binding tape or ribbon to the edge of the sole member, the ribbon or tape overlapping both the upper and lower surfaces of the sole member and being cemented or otherwise secured in place. For optimum appearance the edge finish should be substantially identical in color and texture with the exposed upper surface of the shoe bottom structure (usually a sock lining), but it is not always easy or expedient to provide a binding tape or ribbon which matches the sock lining. Moreover, the application of this ribbon requires skill and is slow, time-consuming, and expensive. At the heel end of the shoe the sock lining overlaps this marginal binding and thus the upper surface of the sole member is made uneven. Furthermore the edge of the sock lining is exposed if it extends to the heel of the shoe.

The present invention has for one of its objects the provision of an improved shoe of the open-end type in which the edge of the middle sole, at the open end of the shoe, is finished smoothly and so as to have identically the same texture and color as the exposed upper surface of the sock lining. A further object is to provide a novel method of making shoes of the open-end variety wherein the exposed end edge of the middle sole may be finished acceptably, expeditiously and at a cost less than that involved in the prior process, and which results in a shoe of improved construction and appearance. A further object is to provide an improved sock lining as a step product in the practice of the improved method of the present invention. Other and further objects and advantages of the invention will be pointed out in the following more detailed description, and by reference to the accompanying drawings, wherein

Fig. 1 is a plan view of an improved sock lining made in accordance with the present invention;

Fig. 2 is a bottom view, to smaller scale, of a shoe upper having the improved sock lining assembled therewith;

Fig. 3 is a view similar to Fig. 2, but showing a middle sole assembled with the upper and sock lining;

Fig. 4 is a view similar to Fig. 3 but showing

2

a cushioning element or "platform" at the fore-part of the shoe;

Fig. 5 is a side elevation of the assembled parts shown in Fig. 4;

3 Fig. 6 is a perspective view, showing the shoe of Fig. 3 to larger scale;

Fig. 7 is a section, substantially on the line 1—7 of Fig. 10;

10 Fig. 8 is a fragmentary perspective view of the heel end of the shoe showing the margin of the sock lining wrapped about the edge of the middle sole;

Fig. 9 is a bottom view of the structure shown in Fig. 5;

15 Fig. 10 is a side elevation of the completed shoe;

Fig. 11 is a plan view of a sock lining of modified construction;

20 Fig. 12 is a perspective view of a lasted shoe having a sock lining like that of Fig. 11;

Fig. 13 is a fragmentary longitudinal section through the shoe of Fig. 12, showing a heel arranged in readiness for attachment; and

25 Fig. 14 is a fragmentary diagrammatic longitudinal section through the toe end of the completed shoe.

Referring to the drawings, the numeral 1 designates a sock lining which may be of any of the usual materials, for instance textile fabric, customarily employed in the manufacture of force-lasting shoes. This sock lining, in accordance with the present invention, is provided with a forward integral extension 2 at its toe end, this extension here being shown as of substantially 30 fan-shape having the forwardly divergent edges 3 and 4 and the curved front edge 5. As illustrated in Fig. 1, the sock lining 1 is also furnished with an integral rear extension 6 extending completely around the heel end of the sock lining and terminating at 7 substantially in the line of the heel breast.

As here illustrated, the shoe upper comprises a vamp 8 having a lining 8^a, the vamp being shaped to provide an opening 9 at the toe of the shoe. As here shown, the quarter portion 10 of the upper is integral with the vamp 8, although it may be a separate part if desired, and this quarter is cut away to leave an opening 11 at the heel end of the shoe, the quarter at this point 40 being merely a strap 12 designed to embrace the ankle.

As here illustrated, the outer member of the upper has a lower marginal integral extension 8^b designed to constitute a wrapper. While here shown as integral, it is to be understood that the wrapper may be a separate element, for example a strip of textile fabric stitched to the outer member of the upper. As illustrated, this wrapper member 8^b extends from the opening at the toe of the shoe to the point 14 which is sub-

stantially at the junction of the heel and shank portions of the shoe.

In assembling the parts the lining member 8^a of the upper is secured to the marginal portion of the sock lining 1 by an inseam 14^a which extends from the open-toe end of the shoe to the point 14. If desired the inseam stitches may pass through both the outer member of the upper and the lining 8^a and through the substance of the sock lining. After the sock lining and upper have thus been united by the inseam, a last L (Fig. 12) is inserted so as to distend the upper and hold the sock lining taut. A middle sole (Fig. 3) is now secured by adhesive to the under surface of the sock lining. As here shown this middle sole 15 comprises a stiff heel and shank portion, a flexible forepart portion 15^a, and a stiff toe portion 15^b. However, the exact construction of this middle sole is no necessary part of the present invention. After this middle sole has been secured in place, a cushion or platform 16 (Fig. 4) of thick resilient material, for example felt, is secured to the under surface of the middle sole by means of adhesive. As here illustrated (Fig. 4) this cushion or platform extends from the toe to the ball of the foot, but it may be extended further toward the heel if desired. The toe extension 2 of the sock lining is now turned downwardly so as to cover and conceal the edges of the toe portion 15^b of the middle sole and also of the toe end of the cushion member 16, the margin 2^a (Fig. 9) of the part 2 being wiped-in beneath the cushion member 16 and secured to the latter by means of adhesive (Fig. 9). The heel extension 6 is likewise turned downwardly and its marginal portion 6^a (Fig. 9) is wiped-in beneath the rear portion of the middle sole 15 and secured to the latter by adhesive. These integral extensions of the sock lining thus form a finish for the exposed portions of the middle sole and its cushion element at the toe and heel ends, respectively, of the shoe and since these extensions are integral with the sock lining, the operation of covering and concealing the exposed edges of the insole and cushion at the heel and toe is greatly facilitated and it is possible for relatively unskilled persons to obtain good results and to provide a finely finished appearance for these portions of the shoe.

The margin of the wrapper portion 8^b of the upper is wiped inwardly and secured by adhesive to the exposed under surfaces of the cushion member 16 and shank portion of the middle sole 15. An outer sole 17 is now secured in place by means of adhesive, the outer sole covering and concealing the turned-in margins of the wrapper. The heel H (Fig. 10) is now attached to the rear end portions of the outer and middle soles by fastening means extending down through the sole members into the heel. A suitable heel pad (not shown) may be applied so as to cover the upper surface of the heel end of the middle sole.

In accordance with a modified arrangement, as illustrated more particularly in Figs. 11, 12 and 13, the sock lining 1^x comprises an integral piece of material including the toe extension 2 but terminating substantially at the lining of the heel breast. To this main portion 1^x of the sock lining an extension 1^y is attached by a seam 18. The portion 1^y of this sock lining may be of different material from the main portion, for example thin leather suitable to form a heel pad, but being flexible and attached by the seam 18, it may readily be folded back beneath the shank portion of the main part of the sock lining.

The upper and sock lining are assembled in accordance with the proceeding above described, the last is inserted, the middle sole applied, and the wrapper and toe extension are wiped-in and secured in place. The outer sole is also applied, but in preparation for the application of the heel H, the heel member 1^y of the sock lining is tucked in, as shown in Fig. 13, so as to expose the heel end of the middle sole. Fastening means, for example nails 19, is now applied for securing the heel H in place and the rear flap 1^y of the sock lining is then withdrawn from beneath the shank portion and after being adhesively coated is laid down over the heads of the fasteners 19 so as to conceal the latter and to form a heel pad.

While certain desirable embodiments of the invention have herein been illustrated and described it is to be understood that the invention is not necessarily limited to these precise details of construction but is to be regarded as broadly inclusive of all equivalents falling within the terms of the appended claims.

We claim:

1. A force-lasted shoe of the open-end type comprising an upper having a wrapper joined thereto, a sock lining united by an inseam to the upper and a sole member which is exposed at the open end of the shoe, the sock lining having an integral portion which extends downwardly, overlaps and conceals the edge of the exposed portion of said sole member at the open end of the shoe, and which has its lower margin disposed beneath the sole member, the lower margin of the wrapper also being disposed beneath said sole member.

2. A shoe of the open-toe type comprising a sock lining, a middle sole having a cushioning element secured to the under side of its forepart, the sock lining having an integral portion which extends downwardly, overlapping the toe end of the middle sole, the free margin of said downwardly extending portion of the sock lining underlying the cushioning element.

3. A force-lasted shoe of the open-end type wherein a sock lining is united by an inseam to the shoe upper, the upper having a wrapper united thereto, a middle sole secured to the sock lining, the sock lining having an integral extension which laps and conceals the edge of the middle sole at the open end of the shoe, the wrapper laps and concealing the edge of the middle sole at other portions of the shoe.

4. A force-lasted shoe of the open-end type wherein a sock lining is united to the shoe upper, a middle sole secured to the sock lining, and a cushioning element secured to the under side of the middle sole, the sock lining having an integral extension lapsing and concealing the edges of the middle sole and cushioning element at the open end of the shoe.

5. A force-lasted shoe of the open-end type wherein a sock lining is stitched to the shoe upper, the upper having a wrapper united thereto, a middle sole secured to the under side of the sock lining, the sock lining having an integral extension lapsing and concealing the edge of the middle sole at the open end of the shoe, the free margin of the extension underlying the middle sole, the margin of the wrapper underlying the middle sole at other parts of the shoe, and an outer sole secured to the middle sole.
